(57) **CLAIM**

The ornamental design for a shoe, as shown and described.

DESCRIPTION

FIG. 1 is a bottom view of a shoe showing my new design; and,

FIG. 2 is a bottom front perspective view thereof. The claim is directed to the perimeter shapes of the three tread elements. The broken lines immediately adjacent to the solid lines represent the bounds of the claimed design and form no part thereof. The remainder of the shoe, shown by the washed out grey portions, form no part of the claimed design.
